UNITED STATES PATENT OFFICE.

EDWARD E. BERTHOLD, OF CHICAGO, ILLINOIS.

ANNUNCIATOR-FIXTURE FOR RESIDENCES.

1,149,973.

Specification of Letters Patent. Patented Aug. 10, 1915.

Application filed July 8, 1912, Serial No. 708,085. Renewed July 9, 1915. Serial No. 38,976.

To all whom it may concern:

Be it known that I, EDWARD E. BERTHOLD, a citizen of the United States, residing at Chicago, in the county of Cook and State of Illinois, have invented certain new and useful Improvements in Annunciator-Fixtures for Residences, of which the following is a specification.

This invention relates to a fixture for a combined electric door-bell, electric door-opener and speaking tube system for residences, especially apartment buildings, and contemplates in particular a fixture comprising a unitary structure on which are mounted the bell, the speaking tube mouth-piece and the push button device for operating the electric door-opener.

In apparatus of this character, as at present installed in buildings, the door bell may be at one point in the apartment and the speaking tube and the push button for the door lock at respectively different points, and having no connection with the bell. It is the purpose of my invention to combine these three devices into a single unitary apparatus, and particularly to provide a fixture to be mounted within the apartment, which fixture is pleasing in appearance and unites all of the annunciator devices into a single device, so that the contractor will have only one device to install in an apartment. In this way the amount of wiring, and also the amount of time and trouble in installation is reduced, and the wall of the room instead of being cut up at several places for mounting the different parts, has only the single fixture mounted thereon.

In the accompanying drawings, Figure 1 is a diagrammatic view of an apparatus which includes a fixture embodying my invention the fixture being shown in front elevation. Fig. 2 is a fragmental section through the wall of a building illustrating said fixture in side or edge elevation.

The fixture is arranged for attachment to the wall A within the apartment and comprises a flat base plate 5 having openings for screws 6 to secure the plate to the wall. Upon this plate, in this instance at its upper end, is mounted a bracket 7 which carries a bell 8. I have deemed it unnecessary to illustrate the operating mechanism of the bell since it may be of any common or preferred form.

9 is a hood secured to the rear side of the plate 5 and partially inclosing the bell mech-

anism. Said mechanism may be mounted on the bracket 7 upon which the bell proper is carried. An opening 10 is provided in the plate behind the bell 8 to receive the operating mechanism.

11 are two terminals on the plate 5 at the edge of said opening, to which terminals are secured wires for supplying electric current to the bell mechanism.

The mouth-piece 12 for the inner end of the speaking tube 13 is secured in an opening in the plate 5, in this instance at the lower end thereof.

Mounted on the plate 5 between the bell 8 and the mouth-piece 12 is a push button device 14 consisting of an annular insulating member 15 secured to the rear side of the plate, a stationary contact terminal 16 mounted on said insulating member, and a spring or yieldable contact member 17 also mounted on said insulating member and arranged to be moved into contact with the stationary terminal 16 by means of an insulating push button 18 sliding in a sleeve 19 which is mounted in an opening in the base plate 5. Screws 20 are arranged to attach wires to the contact members 16 and 17.

The outside door B of the building carries an electro-magnetic locking device 21 of any common or preferred construction, which device is arranged to be operated by the push button device 14 to trip the retaining dog thereof and permit the door to be opened.

A plate 22 which in use is mounted in the outer hallway adjacent to the door 21 has mounted thereon a mouth-piece 23 for the lower end of the speaking tube 13. The plate 22 also carries a push button device 24 comprising a pair of contacts 25.

Current is supplied by a battery 26 of any preferred type, the current traveling from said battery along a wire 27 to one of the terminals 11 of the bell mechanism, thence through said mechanism and the other terminal 11 to a wire 28. This wire is connected to one of the contacts 25 of the push button 24, the other one of said contacts being connected by a wire 29 with the battery. When the push button 14 is depressed the door bell will be rung.

The door-locking device 21 is arranged to receive current from the battery through wires 29 and 30, said door-locking device being connected through a wire 31 to one of the terminals 16, 17 of the push button

structure 14. The other one of said terminals is connected by a wire 32 to the wire 27. Thus when the push button 18 is depressed the door-locking device 21 will be actuated to permit the door to be opened.

If desired, the wire 32 may be dispensed with and the contact member of the push button device grounded on the base plate 5, the latter then serving as a conductor for the current from one of the terminals 11 of the bell to said push button structure.

I claim as my invention:

As a new article of manufacture, a combination fixture of the character described consisting of a flat base plate adapted for at-

tachment to the wall of a building, said base plate having three openings therein, a bracket fixed to said plate adjacent to the edge of one opening and overlying the latter, a bell fixed to said bracket, bell ringing mechanism mounted on said plate behind said bell, a push button structure mounted in another of said openings, and a mouth piece for a speaking tube mounted in the third opening.

In testimony whereof I hereunto affix my signature in the presence of two witnesses.

EDW. E. BERTHOLD.
